CONCRETE PAVEMENT FINISHING
MACHINE

Daniel C. Jones, Port Washington, Wis., assignor
to Koehring Company, Milwaukee, Wis., a corporation

Application October 7, 1948, Serial No. 53,213

8 Claims. (Cl. 94—45)

1

My present invention relates to the art of road building machines of the class designed for laying concrete roads. Speaking more particularly, my invention embodies certain novel improvements in the type of finishing machines disclosed by U. S. patent of William U. Vinton, No. 2,084,068, issued June 15, 1937, which machine is mounted to travel longitudinally over the road subgrade on which concrete aggregates have been laid, and utilizes a longitudinal finishing screed that is moved bodily transverse or crosswise of the road as the machine advances, for giving the final finish to the surface of the deposited concrete aggregates.

Dealing primarily with the objectives of my present invention, it is noted that most concrete roads are formed with a crown for drainage purposes, the crown affording a curvature upwardly from one edge of the road to the middle portion thereof, and thence downwardly toward the other edge of the road, as well known in the art. Now under present road construction methods the crown is gradually reduced to a flat surface around curves and also at the approaches to bridges. The transition in the formation of the road surface from the crown road to a flat road structure is usually performed in a distance approximating eighty to one hundred feet at the approach to the curve, and thereafter the flat surface is discontinued and in a distance of approximately the same amount as previously stated, the surface of the road is brought back to its crown formation from the flat surface at the curve.

Certain improvements of my present invention deal with the problem just referred to in that in my finishing machine there are certain provisions made for adjusting the supporting means for the screed disposed longitudinally of the road and carried by a carriage which traverses the road transversely, such that, during the operation of my machine, such provisions will enable the same to finish either crown or flat surface structures for the road, or any predetermined proportion of crown effect may be made by simple adjustment of the said provisions controlling the operation of the screed and its movement transversely of the road while being carried forward longitudinally of the latter. By my unique provisions for supporting the screed in an adjustable manner as above referred to, it is possible to gradually reduce the crown of the road as a curve section thereof is approached until the curve is actually reached, at which time the finishing machine may be operated so that the road is substantially

2

entirely flat at the curve, and thereafter the reverse operation of the action of the screed may be produced to obtain again the gradual crown as the machine leaves the curve until the point of the road where the full crown effect desired is to be used.

The mechanical instrumentalities by which I am enabled to vary the crown formation of the road surface in finishing until the surface is required to be formed flat, and then so formed, comprise an important feature of improvement of my present invention.

Still another objective of my invention has been to provide special means for adjusting the frame of the machine relatively to the road forms on which the machine operates by utilizing certain controlling adjustments for the wheels which are usually supported on the frame adjacent to the corner portions thereof, and which wheels travel on the road forms. Dealing with this phase of my invention, I might note that the carriage which travels crosswise of the road and supports the longitudinal screed during the finishing operation is mounted to travel on rollers which move along tracks that extend transversely of the road and are affixed to the frame for the purpose mentioned. In machines of my construction the frame of the machine is made in sections so as to enable the sections to be taken apart or collapsed so as to reduce the size of the machine when being shipped to the job or taken from one job to another. When the machine reaches a new job, the sections are bolted together in their proper relation for the particular width of road being handled. Occasionally, due to the above collapsing and restoration of the machine to its working condition, it is found that one corner of the frame may be a small distance, such as an eighth of an inch, low or high, and, under these conditions, the screed would finish the road slightly low or high in that corner, as the case may be. Instead of adjusting certain adjustable tracks provided for the carriage that carries the screed, therefore, I have devised special cam means by which a wheel located at any corner of the machine may be slightly raised or lowered if it should be found, when the machine is set up, that such corner is a little too high or low, and needs slight re-levelling. The camming mechanism of this portion of my invention involves the employment of eccentric mounting shafts for the wheels, the detail features of which, and operation, will be more fully set forth later herein.

In the operation of the longitudinal finishing screed used in the machine of my invention, as

3

the screed moves crosswise of the road it is longitudinally reciprocated for facilitating its smoothing action on the surface concrete being treated thereby. In such movement also the advancing side of the screed picks up materials which tend to pile up slightly at such side of the screed until the latter reaches the side of the road subgrade adjacent to the road form.

Another feature of my invention resides in certain novel means which I provide for raising the screed bodily to enable the carriage to carry the screed to the outer side of said piled up materials so that they may be returned and distributed over the road surface on the next return movement of the screed, toward the opposite side of the road subgrade and road forms located adjacent thereto.

The improvements of my invention are illustrated in the annexed drawings, and in these drawings:

Figure 1 is a general view somewhat diagrammatic in its nature in that small details are not fully illustrated, showing a finishing machine embodying the general structure with which my improvements are used.

Figure 2 is a longitudinal sectional view of the machine bringing out more fully the adjusting instrumentalities for the screed, the arrangement of the carriage that travels on the transversely arranged pairs of tracks, and certain of the other operating instrumentalities that form features of the invention, the view being taken generally on the line 2—2 of Figure 15.

Figure 3 is a transverse sectional view through the frame of the machine, bringing out more clearly the arrangement of the endless chains which are connected to the opposite ends of the screed and move the same crosswise of the road, also bringing out the arrangement of each pair of tracks located near the ends of the screed, one of said tracks being flat and the other being curved for obtaining the flat and crowned surface formations of the road when finished by the machine.

Figure 4 is a fragmentary view showing largely the hydraulic instrumentalities employed for bodily lifting the screed when it reaches a point adjacent the side edge of the road being laid, to carry the screed over the materials that pile up at the advancing side thereof in the manner shown in Figure 14.

Figure 5 is a fragmentary view showing a corner portion of the frame of the machine and the manner of mounting the wheel located at this corner so that it may be adjusted upwardly or downwardly by the camming eccentrically supported shaft.

Figure 6 is a vertical sectional view, somewhat fragmentary in nature as to the frame construction, the section being taken about on the line 6—6 of Figure 5, and bringing out the operating features for the eccentric adjusting shaft.

Figure 7 is a view, partly broken away as to the frame structure, and looking toward adjusting devices seen in Figure 6 from the right hand end of the view to show the adjusting arm and the spring pressed locking pin which cooperates with a selected one of the series of openings in the adjacent guide bracket.

Figure 8 is a sectional view broken away and taken about on the line 8—8 of Figure 7 to bring out the eccentrically disposed journals supporting the shaft which is adjustable vertically and carries a wheel located at each corner of the main frame of the machine.

4

Figure 9 is a vertical sectional view taken about on the line 9—9 of Figure 12, bringing out the arrangement of the two pairs of rollers located at each end of the carriage, one pair supported on the curved tracks for obtaining the desired crown of the road surface, and the other pair adapted to travel along the flat tracks which control the forming of the flat surface of the road when ultimately finished.

Figure 10 is a fragmentary view, enlarged as compared to Figure 2, showing more clearly certain of the adjusting lever, compensating link, and other connecting parts between the carriage and screed as located at each end of the latter; also the track and roller means coacting with the carriage and screed, for controlling the full crown, partial crown, and flat travel movements of the screed. In this view the parts are adjusted for obtaining a road surface of maximum crown, the screed and carriage moving together with full weight of the screed on the carriage.

Figures 11 and 12 are views similar to Figure 10, Figure 11 showing the adjusted positions of the parts as when a part of the screed weight is transferred to the rollers on the flat track for reducing the crown effect of the screed one-half according to the particular adjustments; Figure 12 showing the adjustment of the parts as when controlling movement of the screed such that no crowned finishing effect is obtained, but, instead, flat surface finishing only.

In Figures 10, 11, and 12 the base line x indicates the height of the road forms.

Figure 13 is a sectional view taken about on the line 13—13 of Figure 12 and bringing out the co-operation of the screw shaft on the adjusting lever by which the upper pivotal connection of the compensating link is shifted longitudinally of the lever for various adjustments for a purpose to be more fully described in detail.

Figure 14 is a sectional view showing how the screed works on the surface of the concrete aggregates toward one side of the road, with the materials slightly piling in front of the working side of the screed preliminary to lifting the screed and shifting it to the dotted line position for reverse movement according to operation known to the art.

Figure 15 is a general top plan view of the machine in which certain features of the same not material to the present invention are omitted or not illustrated in detail in order to disclose other parts.

Figure 16 is a detail perspective view showing more particularly the connecting means between the screed supporting levers and the supporting and guide boxes or housings near the ends of the screed.

Describing the general construction of the machine of my invention with the improvements hereinbefore referred to, it will be readily seen from Figures 1, 2, and 15, that said machine comprises a rigid frame composed of the side channels or beams 1, the front cross member 2, and the rear cross member 3, the cross members rigidly attached to the side beams 1.

There will be mounted upon the frame of the machine a suitable motor for driving certain of the wheels of the machine, so that the latter may be steadily moved forwardly along the road subgrade with the wheels rolling on the side forms at opposite sides of the subgrade, as the machine progresses in doing its finishing work upon the concrete aggregate laid upon the subgrade between the road forms.

The motor of the machine will be drivingly connected, as by means of a shaft 4 and gear unit 5 seen in Figure 15, to a longitudinal shaft 6 disposed at one side of the machine for driving the carriage back and forth. The shaft 6 will be equipped with sprocket gears arranged to drive the sprocket chains 7, the lower laps of which are equipped with attachment members 8 that are fastened to hanger brackets or channels 9 rigidly secured at their upper edges to the screed supporting carriage 10, the hanger means 9 forming a part of the general carriage structure and extending transversely in relation to the carriage 10.

In Figure 3 the shaft 6 is shown with its sprockets 6a with the chains 7 passing there-around, said chains extending to the opposite side beam 1 of the frame and around sprockets 11a disposed at the inside of said latter beam 1, and carried by short shafts 11.

The carriage 10 may be made of fabricated metal parts to afford a rigid structure, said parts including depending members 12 near the ends of the top of the carriage, vertical brackets 13 extending downwardly from the inner spaced ends of the members 12 and having secured to their lower ends the narrow platform 14 on which an operator may stand and move toward either the front or rear cross members 2 and 3, respectively, for the purpose of reaching certain of the operating instrumentalities of the adjustable devices for supporting the screed on the carriage.

As previously indicated, my machine being of the longitudinal finishing machine type, the screed employed is a longitudinal screed and is designated 15. The supporting means for the said screed are mounted on the carriage 10 and will shortly be described. It is notable first, however, that the carriage 10 is adapted to operate along two sets or pairs of track members, seen best in Figures 2 and 9, each pair of track members including the outer crown track 16 and the inner flat track 17, one pair of track members 16 and 17 being mounted upon the front cross member 2 of the frame of the machine, and the other pair mounted on a rear cross member 3. The track members 17, which are flat and horizontal, are supported by the adjustable bolts 18 held in place by suitable nuts and passing through the upper horizontal flange of the particular member 3 or 2 on which the track 17 is carried. In like manner the crown track member 16 of each pair is supported by bolts 19 which are attached to the upper flanges of the members 2 and 3 in the same way as are the tracks 17.

For varying the crown of the crown track 16 at the front and rear ends of the frame I contemplate that the bolts 19 may be adjusted upwardly and downwardly to thereby flex the angle plate that forms each track member 16 whereby to modify the arc of curvature of the same. In this manner the arc of the crown to be produced on the road surface materials may be correspondingly varied or changed to meet the requirements of different specifications on different road jobs. This method of varying the curvature of the track members 16 is known to the art and is to be found in prior United States patent of Thorson, No. 1,832,951, issued November 24, 1931, in substantially the same manner as this feature of my invention is used as above described.

I employ a unique supporting mounting between each end of the carriage 10 and screed 15

and the adjacent pair of track members 16 and 17. The supporting means for such purpose is shown clearly in Figures 9, 11, and 12, and referring to Figure 9 it will be observed that at each end of the carriage 10 there is provided a pair of rigidly mounted rollers 20 just underneath the carriage. These rollers 20 are adapted to travel on the lateral flanges that form the track members 16 located outwardly of the track members 17, for each end of the carriage. Thus the rollers 20 move on what I term the crown track members 16 and as they travel on said members the carriage will move on an arc of curvature corresponding with the arcs of curvature of the members 16. Additionally at each end of the carriage 10 I provide a pair of rollers 21 which are supported by posts 22 that slide through guide members 23 formed at the ends of the carriage 10. Each pair of rollers 21 is connected at its upper end by a cross piece 24 so that the two rollers and their mounting means 22 are rigid units. The cross piece 24 is a sort of angle plate and is engaged at its central portion by the head of a bearing screw 25 carried by a lug 26 offstanding inwardly and integrally formed with the sleeve like adjusting lever 27. Said lever 27 is pivoted at its lower outer portion at 28 to a bracket 29 fixed to the adjacent outer end of the carriage 10. The lever 27 is formed at its opposite sides with arc-shaped slots 30 which register transversely of the lever and receive therethrough trunnion pins 31 carried by a nut 32 received in the hollow space of the body structure of the lever 27. At its upper end each lever 27 has a screw shaft 33 passing therethrough and connecting with the nut 32 so as to move said nut up and down on and in the lever 27 incident to rotation of the crank handle 34 at the upper end of said shaft 33. The trunnion pins 31 of the nut 32 are pivotally connected with spaced compensating links 35 at the outer ends of said links, and said links are curved at said outer ends in the direction of the adjacent outer extremity of the carriage 10. Movement up and down of the nut 32 will shift the trunnion pins and upper ends of the links 35 of each of the adjusting units at each end of the carriage 10, the trunnion pins 31 in this operation being shiftable lengthwise of the arc-shaped slots 30 in the sides of the lever 27, and the lever 27, by reason of other connections of the links 35, being able to rock a certain small degree of movement as illustrated in Figure 11 of the drawings, and in Figure 12.

At their lower end each pair of compensating links 35 is attached at the pivotal point 36 to a three-armed lever 37, one of the arms of which is pivoted at 38 to a bracket 39 secured to the upper portion of an adjacent hanger bracket 9 which depends from the carriage 10 as previously described. The third arm of the lever 37 of the screed supporting and track roller controlling unit, one of which is at each end of the carriage 10 is connected by a link rod 40 at the pivot point 41 of said lever arm. The link rod 40 is of the adjustable turnbuckle type, see the turnbuckle 42 in its length, and the lower end of said rod 40 is pivotally connected at 43 to a lifting lever 44. The lever 44 of each of the units now being described is pivoted at 45 to the axis of a top roller 45a of a vertical roller bracket 45b having side vertical rollers 45c. The rollers 45a and 45c support and guide the screed 15 by cooperation with a guide box or housing 46, during the longitudinal movement of the screed later described. One of the boxes 46 is carried by each end of the

screeed 15. The lever 44 at its end opposite the pivot 43 is arranged to extend into a guide member assembly movably supported on the outer side of the depending member 13 adjacent thereto, which member 13 supports one end of the platform or walk 14. In said assembly the guide 47 receives a vertical slide block 48 movable up and down and pivotally attached at its upper end at 49 to the adjacent end of the lever 44. At its lower end the guide block 48 is pivotally attached to a stabilizing link 50 at the point 51 and the opposite end of the link 50 from that pivoted at 51 enters the box 46 and is fulcrumed on roller bracket 45b at the point designated 52 in Figure 11. Each of the units under description is equipped with a link 53 pivotally attached to the lever 44 and the block 48 at the pivot point 49, and the upper end of the link 53 is pivoted to the lower arm of a bell crank lever 54 supported at the lower portion of the member 12 rigid with the under side of the adjacent end of the carriage 10.

As seen in Figure 2, the levers 54 are oppositely disposed, and the upper end of each lever is connected by a link member 55 to a ram operated lever 56 located midway between the two levers 54 and mounted upon a bracket carried by the middle of the carriage 10. The piston rod 57 of a hydraulic ram 58 carried by the carriage 10 near its middle portion is pivotally connected at the pivot point 59 attaching one of the links 55 to the lever 56.

It will be evident from the foregoing that by energizing the ram 58 to supply a pressurizing fluid to force the piston rod 57 in a leftward direction, as seen in Figure 2, the lever 53 may be operated or rocked to correspondingly rock the levers 54 and raise the inner arms of the levers 54, thereby to raise the rollers 45a on the brackets 45b through the action of the lifting links 53. In this manner the screed 15 by means of boxes 46 resting on rollers 45a attached to levers 44 of the screed may be bodily lifted in substantial parallelism with the road surface for the purpose of elevating the screed from a position as shown at the left in Figure 14, to a position such as shown in the right in Figure 14 in dotted lines, at which latter position when assumed by lowering the screed, the movement of the screed across the road is reversed so as to carry the piled up material designated 60 in Figure 14 in a leftward direction or reverse to its movement as previously effected when the screed 15 is moving to the right toward the road form 61.

The control means for the ram 58 may be diversified to a certain extent to the degree of utilizing various such means. In the means illustrated, 62, see Figure 4, denotes the control valve which is readily operable by an operator standing on the walk 14 where he is located quite convenient for operating the screw shafts 33, and clutch levers controlling motion of the machine. There will be supplied the oil reservoir 63, pump 64, and pressure and return lines 65 and 66, respectively, which lead to the valve casing 67 where the control valve 62 is located. For enabling the pressure and return lines 65 and 66 to maintain their connection with the carriage 10 throughout the travelling movement of the carriage upon the tracks 16 and 17, rigid pipe sections 65a and 66a lead from the lines 65 and 66 at coupling points with the latter in a vertical direction. Rigid sections 65a and 66a are mounted upon a spring or otherwise resiliently supported block 68 and are connected by flexible conduits 65b and 66b, re-

spectively, to pipe sections 65c and 66c, respectively, which connect with the valve casing 67. The spring which supports the block 68 is designated 69 and enables the pipe sections 65a and 66a to swing in a direction lengthwise of the frame of the machine under tension incident to the pull of the line sections 65b and 66b as the carriage 10 approaches the limits of its movement toward opposite sides of the frame of the machine. The spring 69 may be attached firmly in any substantial manner to the frame of the machine upon the rear cross member 3.

Referring now to Figures 5 to 8 of the drawings, inclusive, I show therein the manner of mounting the supporting wheels of the machine, which wheels roll upon the road forms 61 at opposite sides of the subgrade, between which forms the concrete aggregates from which the road is built, are laid. It is contemplated that the wheels of the main frame of the machine, designated 70, shall be located near the corners of the frame and the pairs of wheels at opposite sides of the machine are to be adjustable toward and from each other for the purpose of enabling the machine to be used upon roads of different widths. With the above in view, as seen clearly in Figure 6, I provide an axle 71 for each wheel 70, which axle is mounted in bearings at the lower end of vertically movable guide members 72 attached to the front and rear end portions of the machine where each wheel is to be located or mounted. The guide members 72 which carry the axle for each wheel are supported in vertical guides 73 carried by the frame. A yoke member 74 has bearings at its lower leg portions through which the axle 71 passes, and the upper end of the yoke member 74 has bearings for receiving the adjusting shaft 75 which parallels the axle 71 and is disposed spaced above said axle. A screw shaft 76 is swivelly connected at its outer end, which is poly-sided at 76a to receive a turning handle or wrench, and said screw passes through a nut 77 mounted on the yoke member 74. By turning the screw 76 the yoke member 74 which engages the wheel 70 at opposite sides of the hub portion thereof is enabled to cause the wheel 70 to be moved inwardly and outwardly on its axle 71 for adjusting the distance of said wheel 70 from a corresponding wheel at the other side of the machine so that such distance will conform with the distance of the space between the road forms 61 that are used to support the machine in its travel movement forwardly on the road subgrade.

As previously indicated in the statement of my invention, I contemplate that my machine shall be susceptible of slight vertical adjustment of the frame at the corner portions thereof in order to levelize the same and enable the screed 15 to accurately perform its function of forming the crown of the road or making the surface exactly flat, or making formations intermediate such extremes of curvature and flatness. With this in mind, the shaft 75 which supports the yoke member 74 and, by cooperation with the guides 72, supports the wheel 70, is formed at the ends thereof with the eccentric bearing pins 78, the end of the inner one of which pins is pinned at 79 to a shifting and adjusting arm 80. By rocking the arm 80 to the left or right, as seen in Figure 7, the shaft 75 may be turned with the eccentric pins 78 as axis members, whereby to raise the wheel 70 and its axle 71 and the guide members 72, or lower these parts as a unit. The shifting arm 80 is equipped with the spring ac-

tuated latch pin 81 to enter a selected one of the openings 81a arcuately arranged on the cross member 1a which is fixed to the frame structure of the machine. The adjustment required for the wheel 70 in up and down direction incident to the turning of the shaft 75 is very slight, being usually only a fraction of an inch, so that the adjusting means 80, 78, and 75 is readily effective to levelize the machine to a necessary extent at the corner portions thereof where the wheels 70 are located.

As seen in Figures 1, 2, and 15, the shaft 4 operates an eccentrically actuated pitman 82 which is connected with a rocker lever 83 pivoted at 84 on the frame of the machine near the rear end of the machine. At its lower end the rocker member or lever 83 supports one end of a swinging shoe 85 which extends entirely across the frame of the machine at the rear end. There will be two sets of the members 82 and 83, one near each end of the shaft 4, so that the shoe 85 is hung on the lower end of the two rocker levers 83, and during the forward progress of the machine over the road subgrade, upon the road forms 61, the shoe 85 will be moved forwardly and backwardly. On the rear end of the screed 15 are carried two vertically extending posts 86, one in front and one in rear of the shoe 85. Thus, as the screed is carried back and forth transversely of the frame of the machine to perform its finishing operation, the shoe 85 will always be maintained in connection with the screed and in engagement with the posts 86, whereby to impart to the screed a short forward and rearward movement in a longitudinal direction while the screed is being operated across the width of the road aggregate laid down between the forms 61. This feature of my invention is the same in general principle as disclosed in the patent of Vinton previously identified herein. In such longitudinal movement rollers 45c in boxes 46 guide the screed 15.

As shown in the drawings, the adjusting levers 27 are provided on the sides thereof with scale marks for coaction with the pivots 31 of the compensating links 35 to indicate the degree of adjustment of the connection between the links 35 and said lever. The scale marks are identified by scale numbers ranging from "1" adjacent to the pivots 28 of the levers 27, to "10" adjacent to the upper ends of the slots 30 in the levers. The purpose of the said indicia will appear in the following description of the operation of my invention.

With the construction of my machine as above set forth in mind, it will be understood that the screed 15 finishes the road to the same crown as controlled by the outside tracks 16 when the links 35 are adjusted to determine such crown. Moreover, the screed will finish the road to any proportional crown down to a flat surface as controlled by the inner tracks 17, dependent upon the adjustment of the compensating links 35 for transferring the weight of the screed partly or entirely to the flat track rollers 21, during traverse of the carriage and screed across the road. The outside pairs of rollers 20 at the ends of the carriage 10 always carry the weight of the carriage and run back and forth on the track members 16 which are set to the predetermined crown. The carriage 10 always follows the curved path of the crowned track members 16 as the carriage traverses crosswise of the road back and forth from side to side. The inner pairs of rollers 21 run on the flat track members 17, as previously

described, but these rollers can move up and down incident to the sliding action of their posts 39 in the ends of the carriage 10. Thus by adjustment of the links 35 relatively to the levers

5 27, whereby the weight of the screed 15 is transferred in part from the carriage 10 to the abutment or cross members 24 and thereby to the rollers 21 on the flat tracks 17, the crowned surface produced when the screed 15 is wholly supported by the carriage 10, may be eliminated entirely, or partially according to the requirements at the particular curve of the road which is in process of finishing.

The operation of the machine in producing a 15 full crowned road surface, and in reducing the curve of the crown gradually, and entirely eliminating the crown, will now be described upon reference to Figures 10, 11, and 12 of the drawings which are sectional views through the machine 20 at a central point in the lengths of the crowned tracks 16 located at the middle of the road, at which point these tracks are highest from the road forms. In each of these views the height or 25 top plane of the road forms, constituting the machine tracks, is denoted by the line X, and a line Y is employed to indicate the maximum crown of the finished surface and amount of crown eliminated when less than the entire curve of the crown is to be produced.

30 The condition of operation depicted by Figure 10 will first be set forth. Of course the links 35 and their connections to the screed 15, and the levers 27 and their connections to the links 35, will be as shown in Figure 10, for both sets of said parts connecting the carriage 10 and the screed 15, one set only being illustrated.

Now with the links 35 adjusted with their pivot connections 31 in what may be called zero positions on the scale on each lever 27 (Figure 10) it will be apparent that during the movement of the carriage 10 across the road, the weight of the screed 15 is supported solely by the carriage 10. Therefore, the screed will follow at its finishing edge the same curve or contour that the carriage 45 10 does as the latter rides on track rollers 20 and curved tracks 16, from one end of the tracks to the other, and as many times as the carriage is moved back and forth.

Under the above condition of operation, the 50 rollers 21 and flat tracks 17 perform no operating function. The rollers idle on the tracks 17, and the posts 22 slide down and up in their guides 23, as the carriage and screed ride up and down, respectively, on the curve of the crown tracks 16. 55 The cross or abutment members 24 move with their connected posts 22, and the members 24 are out of engagement with the stop or abutment screws 25 on the levers 27.

60 The operation with the parts as in Figure 10 will produce a full crowned road surface with the maximum of curve or crown obtainable by the machine, indicated in said figure by the amount of space between the lines X and Y. This crown is fixed as to height, relatively speaking, by the distance between the plane of the flat tracks 17 and the top point of the curve of the crown tracks 16, see lines at Z in Figures 10, 11, and 12.

70 Now let us suppose that the machine hereof has been used to the extent of gradual elimination of the full crown finishing action, on a curve in the road, so that reduction of the crown (elimination, in other words) to one-half of the normal maximum will be required. The operator will actuate the screw shafts 33 to shift the pivot

points 31 of links 35 to the number "5" positions on the indicia scales of the levers 27, as seen in Figure 11. Thus, when the carriage 10 and screed 15 are caused to travel across the road after the said adjustment of the links 35, the levers 27 by the screws 26 engagement with the cross members 24 transfer a part of the weight of the screed to the flat track rollers 21. Therefore, as the screed 15 moves back and forth with the parts so adjusted, the levers 27 are movable downward, see Figure 11, to an extent governed now by the change in the adjustment of the pivot connections 31 (from the position of Figure 10), and this action during the movement upwardly of the rollers 20 relatively to the rollers 21 allows the screed 15 to move on a curved arc such as to eliminate one-half (five-tenths) of the crown of the road obtained according to the adjustment of the parts in Figure 10. Thus as the carriage 10 moves across the road it follows the path of the curved tracks 16, while the screed 15 moves downwardly and travels in an arc of movement establishing a crown of one-half the depth of that obtained when the parts are adjusted as in Figure 10. The distance of movement of the levers 27 in the Figure 11 illustration is indicated by the arc marked *a* between pivot 31 and the arrow shown. Obviously, if the pivots 31 were adjusted to the number "3" positions on levers 27, the extent of reduction of the crown would be three-tenths of the total maximum crown depth obtainable, and so on.

With the links 35 pivots in any position from those indicated as "1" to "10," the levers 27 through the stop screws 25 engage or rest on the cross or abutment members 24, enabling the screed 15 to move down one or more tenths extent of movement, as determined by the scale adjustments of the pivots 31 for shifting movement of the levers 27, and the transfer of weight of the screed 15 to the flat track rollers 21 as set forth, during the traversing movement of the screed.

When the pivots 31 are adjusted to the upper ends of the scales of levers 27, as indicated by the number "10" indicia, ten-tenths of the crown depth of the screed controlled movement is eliminated. In other words, in the number "10" position the relative up movement of the carriage 10 on the crown tracks 16 has no effect whatsoever to raise the screed in its travel. The carriage merely travels its usual course on the curve of the tracks 16 while during all of the said travel the weight of the screed 15 as supported by the rollers 21 on the flat track 17 maintains the screed in the path of straight travel of the tracks 17. The screed never rises under this condition which is depicted in Figure 12 of the drawings, and therefore the road materials on the subgrade are finished flat. Of course, in the operation of the screed at the number "10" positions of the parts, as referred to, and shown by Figure 12, since the carriage 10 rises on the crown tracks 16, in the traversing movement of the carriage and screed over the road materials, the levers 27 will rock down from their position of Figure 10 to that of Figure 12, the maximum throw of said levers, for eliminating all crown finishing effect of the screed, as shown by the arc *b* on Figure 12.

Summarized, it may be noted that an operator of the machine described would have the links 35 adjusted to their zero positions of Figure 10 during ordinary general use of the machine in finishing the road surface. As a curve in the road

is reached, the operator will begin reducing the crown finishing, or elimination of crown effect, by shifting at intervals the link 35 pivots 31 to number "1" positions, then to the number "2" positions, then to number "3" positions, and so on, up until the number "10" positions are reached, whereupon the road at the curve may be finished with a flat surface. From the flat surface formation to the full crown surface involves merely a reversal of the order of adjustment, namely, periodic adjustment of the pivots 31 to number "9," "8," "7" positions and so on down until zero positions restore the full crown finishing operation of the screed.

15 It is necessary to adjust the screw shafts 33 on opposite ends of the carriage 10 for different indicia setting in the process of making the transition from a flat to crown road, and vice versa. Thus if the indicia setting on the forward unit 20 27 is at "5," then that for the rear unit 27 would be at "4" when going from the flat to crowned road surfacing or finishing. The reverse order of setting would be used in going from a crowned road surface to the flat finishing.

25 The operator standing on the platform or catwalk 14 watches the progress of the screed 15 crosswise of the road, and when the screed nearly reaches the road form 61 at one side of the road, he will elevate the screed so that it will pass over the material designated 60 in Figure 14, in advance thereof, by operation of the hydraulic controlling valve 62. Then the screed 15 will be lowered just above the form 61, and the movement of the screed at this time is reversed, and 30 the material at 60 is pushed back toward the opposite side of the road to enter small pockets or depressions that may have been left in the surface on the first mentioned movement of the screed toward the form 61 above mentioned.

35 40 One way to explain the peculiar action of the mechanism of this invention is to point out that the member comprised of rollers 21, post 22 and angle plate 24, is a control member adapted to influence the crowning action. This is accomplished by reason of the fact that the lever 27 is connected at the point 28 and is in effect rollably supported with the carriage 10 by rollers 20 on the crowned track 16. Another point constitutes the trunnion pin 31 at the end of the link 35, from which the screed 15 is suspended and is movable along the lever in the slot 30.

45 50 A lug 26 projects into the path of vertical movement or travel of the control member, and as the carriage 10 rises and falls in its travel 55 across the frame, the control member is adapted to abut the lug and thus prevent the lever 27 from moving farther downwardly at its outer end. The amount of this movement is regulated by the adjustment of the point 31 in the slot 30, 60 effected by manipulating the crank 34. It should be understood that movement of the point 31 from the position of Figure 10 at which maximum crowning movement is provided, to the position of Figure 12, effects gradual elimination of 65 the crowning action of the screed, and that as seen in Figure 10, the lug 26 does not coact with the angle 24 during movement of the carriage; but in Figure 12, the lug is in constant engagement with the angle 24 throughout the transverse movement of the screed.

70 Still another way to describe the action of the crown controlling arrangement heretofore set forth is to state that the path of travel of the carriage 10, is always that of the crowned track 16, since the carriage is supported by rollers 20

connected thereto. The carriage 10 thus always follows the arc determined by the crowned track. As shown in Figure 10 the maximum amount of crown is afforded with the weight of the screed entirely supported through rods 40, levers 37, compensating links 35, levers 27, on brackets 29 fixed to the outer ends of the carriage 10. Adjustment of the fulcrum points 28 and 31 through crank handle 34 from the position of Figure 10 to that of Figure 11 will clearly effect a lowering of that end of the screed. This will bring the bearing screw 25 in position close to the angle plate 24 which is supported on the rollers 21 at the lower ends of posts 22, the rollers 21 being movable along the flat track 17.

If thereafter the carriage 10 moves from its central position intermediate the sides 1 of the machine, to the position as shown in Figure 15 for example, the crosspieces 24, moving in planes parallel to the tracks 17, will have come into contact with the bearing screws 25 and the weight of the screed 15 will have been transferred to the rollers 21 by such abutment and the levers 27, links 35, levers 37, and rods 40 connected to the levers 44, by which the screed is supported. This will have been caused by reason of the fact that while the carriage 10 has in effect been moving downwardly from the high points of the crowned tracks 16 as shown in Figures 10, 11, and 12 toward the lower outer ends of the said tracks, yet the positions of the crosspieces 24 has remained the same with the said bearing screws 25 in contact therewith. Further if the handles 34 are moved into the positions shown in Figure 12 when the carriage 10 is at the center of the machine as respects its sides 1, subsequent movement of the carriage to one side of that center point will cause the weight of the screed to be transferred to the flat track rollers through the links and levers previously described. Thus the points at which the weight of the screed will be transferred from the rollers 20 to the rollers 21 may be varied by the adjustment above mentioned, between none at all as shown in Figure 10 to the maximum as shown in Figure 12, the crown of the finished road being thus correspondingly varied from the maximum of Figure 10 to none at all in Figure 12.

The abutment screws 25 are installed and adjusted during the erection of the machine in the shop and are used to compensate for inaccuracies in the shape of the castings used. These screws do not require adjustment in the field.

Having thus described my invention, what I claim as new and desire to secure by Letters Patent of the United States, is:

1. In a finishing machine, in combination, a traveling supporting frame, a carriage mounted thereon, means to move the carriage back and forth across said frame on a predetermined path, a finishing screed for action on road surface materials, members connecting the screed to the carriage to move across the frame with the latter, spaced guide members mounted on the frame for vertical movement, and having bearings thereon, a shaft received in said bearings, eccentric pins on the ends of the shaft mounted in the frame, an arm secured to the shaft and adjustable to turn the same for shifting the shaft and guide members up or down on said pins, an axle carried by said guide members, and a wheel supported on said axle.

2. A machine as claimed in claim 1, combined

with a yoke connecting the shaft and axle and engaging the wheel for moving same, and an adjusting member on the frame connected to said yoke to slide same lengthwise of the shaft and axle and thus move the wheel horizontally relatively to the frame.

3. In combination, a frame, and a wheel supporting unit therefor comprising a wheel, an axle on which the wheel is slidably, a yoke engaging the wheel to move same along the axle, a shaft mounted in bearings on the frame supporting the yoke, guide members movable vertically on the frame and carrying said axle, a screw on the frame coacting with the yoke to shift same and wheel along the shaft and axle, and means to move the shaft vertically and bodily on the frame to raise or lower the wheel.

4. In a finishing machine in combination, a traveling supporting frame, a transverse curved track and flat track mounted on said traveling frame, a carriage supported on said curved track for back and forth movement across the frame, a lever pivoted to a fixed pivot point on said carriage, a control member rollably supported on said flat track and supporting said lever at a point spaced from said fixed pivot point, a longitudinal finishing screed for action on road surfacing materials, means for suspending said finishing screed from a point on said lever, and means to adjust said point along said lever to vary the influence of said control member to vary the crown.

5. The combination as claimed in claim 4, wherein the lever is pivotally connected to the carriage at the said one point, an arcuate slot is provided in the lever, a link having one end comprising the other point is movable in said slot, and the adjusting means compels movement of said one end.

6. The combination as claimed in claim 4, wherein the lever is provided with a portion adapted to engage said control member, said other point comprises a pivot member movable along said lever, and the adjusting means includes a screw member for moving said pivot member.

7. The combination as claimed in claim 4, wherein the lever includes a projecting portion, the control member comprises a vertically movable part adapted to engage said portion, and the said other point is movable in an arcuate slot in said lever.

8. The combination as claimed in claim 4, wherein the lever is pivoted at said one point to the carriage, the lever is provided with a portion for engagement by the control member, the other of said points constitutes the end of a link pivotally engaged with said lever and movable in a slot therein, said link being connected to said screed, and the adjusting means includes a crank for moving the pivoted end of said link in said slot.

DANIEL C. JONES.
